UNITED STATES PATENT OFFICE

FREDERICK W. HORN, OF BROOKLYN, NEW YORK.

DESIGN FOR BOOK-CLASPS.

SPECIFICATION forming part of Design No. 11,788, dated May 25, 1880.

Application filed March 29, 1880. Term of patent 7 years.

To all whom it may concern:

Be it known that I, FREDERICK W. HORN, of Brooklyn, in the county of Kings and State of New York, have invented a new and ornamental Design for Book-Clasps; and I do hereby declare that the following is a description of the same.

This design for book-clasps relates to the swinging portion that extends from one cover to the other and is swung back and forth in clasping and unclasping the book.

The design of this clasp is shown in the accompanying drawings, in which—

Figure 1 is a plan, and Fig. 2 is a side view, sectionally, of the cover.

The swinging portion *a* of the clamp has the general shape of a horseshoe, the surface of which is made in imitation of the channel and nail-heads at *b*, and with projections at *c*, in imitation of calks.

At the ends of the clasp there are lateral projections at each side, as at *i*, and these are

adjacent to the pivot-studs *e e*, which studs *e* have rounded ends and tapering bodies, as 25 seen in Fig. 2. These studs *e* and projections *i* form ornaments to the ends of the clasp.

f and *g* are the bent clips upon the edges of the book-covers.

This design is highly artistic, and the appearance of the clasp and studs is ornamental, and greatly enhances the beauty of the binding upon books.

I claim as my invention—

The ornamental design for a book-clasp, 35 consisting of the horseshoe-shaped clasp with the projections *i i* at each side of the ends, and the round-ended studs, with tapering bodies, adjacent to such projections *i*, as shown.

Signed by me this 22d day of March, A. D. 40 1880.

FRED. W. HORN.
